LIFE SAVING DEVICE FOR SUBMARINES

Filed May 27, 1929

UNITED STATES PATENT OFFICE

HENRY ECKEL AND HARRY SCHUENHOFF, OF HAMILTON, ONTARIO, CANADA

LIFE SAVING DEVICE FOR SUBMARINES

Application filed May 27, 1929. Serial No. 366,368.

This invention relates to new and useful improvements in life saving and safety devices for use on submarines, as described in the present specification and illustrated in the accompanying drawings which form part of same.

The invention consists essentially of a leak-proof chamber adapted to be detachably secured to a submarine, and novel means of establishing communications between or for detaching said chamber from the submarine and sealing said communications against leakage both into the submarine or into the chamber, as pointed out in the claim for novelty following a description containing an explanation in detail of an acceptable form of the invention.

The objects of the invention are to provide a life saving device for submarines which may be readily brought into operation and in which the occupants of a submarine may be safely conveyed to the surface of the water from a submerged vessel; to construct such a safety device in which the occupants may remain afloat without injury from the elements for an indefinite period and which affords means for the storage of food supplies and the like; to construct a submarine life boat that may be readily adapted for use on existing types of submarines without requiring costly alterations or entailing expensive labour charges; to devise a submarine life boat that will safely convey an indefinite number of the occupants of a submerged submarine to the surface without exposing them to the extreme pressures met with in certain depths of water; to effect means whereby the rising speed of the life boat may be controlled throughout its ascent to the surface of the water from a submerged submarine; to prevent to a large extent loss of life due to the accidental sinking of submarines; and generally to provide a device of this description capable of accomplishing the aforesaid results and purposes.

In the drawings, Figure 1 is a part section and part side elevational view of the device complete as installed on a submarine.

Figure 2 is a plan view of Figure 1.

Figure 3 is a plan view of a safety door into the submarine.

Figure 4 is a section view taken on lines 4-4 in Figure 3.

Figure 5 is a sectional view taken on lines 5-5 in Figure 2.

Like numerals of reference indicate corresponding parts in the various figures.

Referring to the drawings, the numeral 10 indicates the device complete. 11 is an upper portion of the hull of a submarine. 12 is a leakproof chamber of sufficient size to float on the surface of the water with its load, which comprises the passengers, various supplies, control and driving mechanism and the enclosing walls 13 of the chamber itself. The walls 13 of the chamber 12 are preferably formed of a tough light weight metal and may be suitably braced in any well known manner compatible with the usual methods of construction in pressure resisting chambers. The chamber 12 may be constructed in various shapes according to the wishes of the designer.

In Figures 1 and 2 I have shown a feasible design in which the forward part 14 is tapered to provide a suitable prow. The rear portion of the chamber 12 is rounded to form the stern. A raised portion 16 is formed on the upper side of the chamber 12 and has suitable ventilating valves 17 formed in the side walls thereof. A leakproof cover 18 is pivotally mounted on said raised portion 16 and may be opened when the device is floating on the surface of the water.

The central portion of the base 20 of the chamber 12 is formed with a flattened under surface adapted to conform with and bear on the deck 21 of a submarine, as at 22. An opening 23 is formed in the base portion and is of sufficient size to allow for the passage of the passengers therethrough. A manhole 24 is formed in the deck of the submarine, slightly smaller than the opening 23, so as to provide the peripheral portion 25 therearound, projecting beyond the periphery of the opening 23 when said opening is brought into alignment with the opening 24. A plurality of screws 26 passing through openings formed in the flattened base portion 20 are

threaded into openings 27 formed in the deck 21 and serve to detachably secure the base 20 of the chamber 12 to the deck 21 of the submarine and to retain the openings 23 and 24 in proper alignment with each other. Communications are now established between the chamber 12 and the interior of the submarine 11 by way of the openings 23 and 24. A suitable leakproof gasket 30 is preferably inserted between the base 20 and the deck 21 at this point to prevent leakage of any sort. The head of each cap screw 26 is enclosed in a leakproof casing 31, substantially as shown in Figure 4. A socket wrench 32 mounted on 15 and aligned with a shaft 33 is situated in each casing 31 and directly above the cap screw head. The shaft 33 is reciprocally and rotatably mounted in the casing 31 and is surrounded at its mounting by a suitable packing gland 34. In order to seal the opening 23, a door 35 is preferably hingedly mounted as at 36 to the upper side of the base 20. The door 35 extends over the opening 23 and may be secured in its closed position by the 20 cap screws 37 passing through openings 38 formed therein and threaded into the base 20 as at 39.

A suitable leakproof gasket 39A is preferably inserted between the door 36 and the base 20 to ensure a leakproof joint therebetween.

A door 40 similar to the door 35 is hingedly mounted to the underside of the deck 21 as at 42 and is adapted to swing to a closed position under the opening 24 formed in the deck 21. The door 40 may be secured in its closed position by cap screws 43 passing through openings 43A in the portion 25 of the deck 27 and threaded into the door 40 as at 44. A suitable leak proof gasket 45 is preferably situated between the door 40 and the deck 21 to prevent leakage.

Suitable fore and aft braces 46 extending upwardly from the deck 21 and secured thereto to be provided to support the chamber 12 and are secured thereto by cap screws 26A passing through the walls of the chamber and threaded into said braces. A casing 31A having a socket wrench mounted therein similar to the casing 31, is mounted over each of said cap screws 26A similar to that shown in the former case at 31.

Suitable ports or sights 60 may be formed in the walls of the chamber 16 and are covered 55 with a heavy pressure resisting glass and properly sealed against leakage. In order to retain the door 40 in its closed position under ordinary circumstances, when the safety device 10 is not in use, suitable cap screws 61 are passed through openings 62 and from the under side of said door and threaded into the deck 21 as at 63.

A suitable power unit 50 adapted to drive a propeller 51 may be mounted in the chamber 12 and utilized to propel the device along

the surface of the water, and a steering apparatus 53 is installed at the stern of the device and is adapted to be operated from the interior thereof. As the method of steering and propelling the device and the method of installation of the water ballast tanks are all well known to the art, it is considered unnecessary to specify particularly the constructional details involved in these different mechanisms.

In the operation of this invention, the device 10 is secured to the hull of the submarine by means of the cap screws 26A. Communications between the submarine and chamber 12 from the life boat are established by bringing the covers 35 and 40 to their open position. A ventilating valve 17 is retained in its closed position to prevent leakage of water into the chamber 12 and the leakproof chamber 18 is retained in its closed position for 85 the same reason.

If the submarine to which the life boat is attached is unable to rise to the surface of the water due to accident or other causes, and the crew desire to escape therefrom, the crew or passengers in the submarine after entering the chamber 12, pivot the cover 40 to its closed position and effectively seal the opening 40 by threading the cap screws 43 to their final position. The cover 35 is then pivoted to its closed position and effectively sealed by threading the cap screws 37 to their final position to bring the cover 35 into close engagement with the leakproof gasket 39A.

The chamber 12 may now be detached from the submarine by unscrewing the cap screws 26 from the deck 21 and by unscrewing the cap screws that secure the braces 46 to the side walls 13. The device now is free to float to the surface of the water. If the vessel is at any depth, the water ballast tanks should be flooded to prevent too precipitous an ascent to the surface of the water. After reaching the surface, the air valves 17 may be opened to aid in ventilation and the propelling and controlling mechanism, as indicated at 51 and 53, is then brought into operation. The cover 18 may now be opened if weather conditions permit.

It is to be noted of course that suitable oxygen producing apparatus may be installed, but as this class of device does not involve invention and is well known to the art, it need not be described.

What we claim is:

In a life boat for submarines, a leakproof enclosed vessel adapted to be secured to the deck of the submarine and having a flattened under-surface with a central opening adapted to be in alignment with an opening in the submarine deck, hinged doorways closing in the openings, a plurality of bell-shaped casings bolted to the base portion of the vessel, each of said casings having a water-tight chamber forming a container for a cap screw

adapted to project through the base portion of the boat and into the deck of the submarine and forming a journal member for a socket wrench adapted to engage with the
5 head of the vessel in the water-tight chamber, and projecting upwardly from the bell-shaped casing and adapted to be manually operated, a plurality of brace members bolted to the submarine deck and bolted at the
10 other end to the underside of said vessel by means of cap screws enclosed in bell-shaped casings, and a plurality of ballast tanks secured in said vessel.

Signed at the city of Hamilton, this 23rd
15 day of February, 1929.

HENRY ECKEL.
HARRY SCHUENHOFF.
